(57) **CLAIM**

We claim the ornamental design for a box for storage of a tool for chip removing machining, as shown and described.

DESCRIPTION

FIG. 1 is a top view of a box for storage of a tool for chip removing machining.

FIG. 2 is a bottom view of the box of FIG. 1.

FIG. 3 is a side view of the box of FIG. 1.

FIG. 4 is a front view of the box of FIG. 1.

FIG. 5 is another side view of the box of FIG. 1.

FIG. 6 is a rear view of the box of FIG. 1.

FIG. 7 is a top perspective view of the box of FIG. 1.

FIG. 8 is a top view of the base part of the box shown in FIGS. 1-7.

FIG. 9 is a bottom view of the base part of FIG. 8.

FIG. 10 is a side view of the base part of FIG. 8.

FIG. 11 is a front view of the base part of FIG. 8.

FIG. 12 is another side view of the base part of FIG. 8.

FIG. 13 is a rear view of the base part of FIG. 8.

FIG. 14 is a top perspective view of the base part of FIG. 8.

FIG. 15 is a top view of the lid part of the box shown in FIGS. 1-7.

FIG. 16 is a bottom view of the lid part of FIG. 15.

FIG. 17 is a side view of the lid part of FIG. 15.

FIG. 18 is a front view of the lid part of FIG. 15.

FIG. 19 is another side view of the lid part of FIG. 15.

FIG. 20 is a rear view of the lid part of FIG. 15; and,

FIG. 21 is a bottom perspective view of the lid part of FIG. 15.
